(Cl. D92—26)

The FIGURE is a plan view of a portion of a plastic tablecloth showing my new design.

A complete design unit, comprising one-quarter of a complete tablecloth, is shown in the drawing, and this unit is reproduced in the other three-quarters of the tablecloth.

The section disclosed is a representation of a dark article shown over a light background to bring out the details of the design, the variations in shading resulting from variations in the number and size of minute perforations through said article.

I claim:

The ornamental design for a plastic tablecloth, as shown and described.
